Robert H. Crowle, Berwyn, Ill., assignor to Charles E. Jones and Associates, Inc., Chicago, Ill., a corporation of Illinois

Application April 8, 1959, Serial No. 55,409

Term of patent 14 years

(Cl. D34—15)

Figure 1 is a perspective view of a tricycle, showing my new design;

Figure 2 is a plan view of the tricycle;

Figure 3 is a side elevation of the tricycle; and

Figure 4 is a rear elevation of the tricycle.

The essential features of my new design reside in the portions shown in solid lines on the drawing.

I claim:

The ornamental design for a tricycle, substantially as shown and described.
